Primary Examiner — Karen E Eldridge Powers*(74) Attorney, Agent, or Firm* — Amster, Rothstein & Ebenstein LLP(57) **CLAIM**

The ornamental design for a bottle brush, as shown and described.

DESCRIPTION

FIG. 1 is a front elevation view of a bottle brush showing our new design;

FIG. 2 is a side elevation view thereof;

FIG. 3 is a rear elevation view thereof;

FIG. 4 is an opposite side elevation view thereof;

FIG. 5 is a perspective view thereof;

FIG. 6 is a top plan view thereof; and,

FIG. 7 is a bottom plan view thereof.

The broken lines illustrate environmental features and form no part of the claimed design.
